UNITED STATES PATENT OFFICE

163,639

HAND SEWING GUIDE

Myrle J. Rumpel, Hayward, Calif.

Application July 17, 1950, Serial No. 11,231

Term of patent 14 years

(Cl. D3—19)

To all whom it may concern:

Be it known that I, Myrle J. Rumpel, a citizen of the United States and a resident of Hayward, Alameda County, California, have invented a new, original, and ornamental Design for a Hand Sewing Guide, of which the following is a specification, reference being had to the accompanying drawing, forming part thereof.

Figure 1 is a front perspective view of a hand sewing guide, showing my new design; and

Figure 2 is a rear perspective view thereof.

This sewing guide is designed for hand use.

I claim:

The ornamental design for a hand sewing guide, substantially as shown and described.

MYRLE J. RUMPEL.
